CLAIM

The ornamental design for an optical sight mount, as shown and described.

DESCRIPTION

FIG. 1 is a top isometric view of an optical sight mount according to the present disclosure;

FIG. 2 is a bottom isometric view of the optical sight mount shown in FIG. 1;

FIG. 3 is a front elevational view of the optical sight mount shown in FIG. 1;

FIG. 4 is a back elevational view of the optical sight mount shown in FIG. 1;

FIG. 5 is a right side elevational view of the optical sight mount shown in FIG. 1;

FIG. 6 is a left side elevational view of the optical sight mount shown in FIG. 1;

FIG. 7 is a top plan view of the optical sight mount shown in FIG. 1; and,

FIG. 8 is a bottom plan view of the optical sight mount shown in FIG. 1.

The broken lines represent portions of the optical sight mount that form no part of the claimed design.

1 Claim, 7 Drawing Sheets
